UNITED STATES PATENT OFFICE

2,007,667

BOAT ANCHOR

George Edwin Stubbs, Miami, Fla.

Application April 18, 1933, Serial No. 666,706

2 Claims. (Cl. 114—208)

My invention relates to improvements in boat anchors, and has for its object the production of a releasing boat anchor, built in parts so that its shank will appear and operate as one unit, just the same as an anchor of the common type having a one piece shank, and can be released from an obstruction when one or the other of the flukes are fouled on the bottom of a body of water, and of such construction the danger 10 of loss to a vessel is reduced to a minimum.

In the accompanying drawing,

Figs. 1 and 4 are perspective assembly views of my improved anchor.

Figs. 2 and 3 are respectively side and edge views of the auxiliary shank portion according to the invention.

Fig. 5 is a detail view of the stock portion according to the invention.

Numerals 17—17 in the drawing indicate the controlling shank bars, 5 the crown, 2 the auxiliary shank, 12 its groove between twin tongues, 14 the head and 13 its tongue and shoulders; 6—6 the independent pivoted arms; 7—7 the flukes, 8—8 the fins, of an anchor constructed in accordance with my invention.

The auxiliary shank 2 and the crown 5 are preferably made for this anchor in one piece, although the crown is not necessary when the shank is applied to other types such as the navy or similar anchors. The crown 5 is made for this anchor of a width and thickness to allow the connection of stock 1 central of its width, and depth below the pivot bolt, and is shaped on either end to form a stop for independently pivoted arms 6—6. Also to receive and hold said arms in position by pivot bolt 10 to allow free movement of said arms to engage the bottom in the regular manner and to fold against shank for non-fouling when in use and for stowing when not in use as an anchor. The head 14 is constructed with pivot studs cast integral with head in its lower end at the intersection of the tongue for strength at this point of construction and are threaded to receive nuts 19—19 for a purpose to be presently described.

The controlling shank bars 17—17 are preferably made for the anchor shank in two straight flat bars, pivotally secured at their lower end by a suitable pivot bolt 15, to allow free movement and pivotally secured at their top or head end by pivot studs 15—15 threaded to receive nuts 19—19 to be set tight against controlling shank bars 17—17 on each side of head 14 to retard the movement of head 14 from turning on its pivot only to the angle of the pull under a heavy strain

during its functions as an anchor the same as an anchor of the common type with a one-piece solid shank. It will be noticed the twin tongues forming the groove 12, at the upper end of auxiliary shank 2, engages the tongue 13 in the lower end of the head 14 close up to the lower extreme of the pivot studs 15—15, and the upper extremity of the tongue 13, or on a line with projecting shoulders between the two. This construction as can be readily seen will reduce the 10 leverage strain to smallest minimum possible, and when the head 14 is turned on its pivot at about right angles to the controlling shank 17—17, thereby preventing the auxiliary shank 2 from passing between controlling shank bars 17—17, 15 without one or the other of the twin tongues on the upper end of the auxiliary shank 2 striking the lower downward projecting shoulder when the head 14 is turned on its pivot at right angles to the controlling shank bars 17—17, after once 20 being released from an obstruction from one side or the other, the head will remain in its right angle position because the pressure applied by nuts 19—19 against controlling shank bars 17—17 retards the turning of head 14 on its pivot. When 25 the tide changes the anchor will turn over and its opposite arm and fluke will contact the bottom, and the surging of the vessel on cable will cause the head 14 to turn on its pivot and resume its normal parallel position, and the 30 tongue 13 in lower end of head 14 will gear in the groove between twin tongues on the upper end of the auxiliary shank 2, and hold the auxiliary shank 2 captive, central between and parallel with the controlling shank bars 17—17, and 35 the head 14, and appear and operate as an anchor with a one-piece shank.

At any time a fluke is fouled on an obstruction, the anchor shank will continue to perform as an anchor with a one-piece shank until it is 40 desired to leave the moorings. A vessel can be moved to the opposite direction and the surge of the vessel on anchor cable will turn the head 14 at right angles to the controlling shank bars 17—17 and release the auxiliary shank 2 from its 45 captivity with head and allow the controlling shank 17—17 to turn on its pivot thru about $\frac{1}{4}$ arc as illustrated in dotted line position in Fig. 4 and stop against the upper fluke. This position will place the controlling shank 17—17 in line 50 with the points of both flukes 7—7 and the fouled fluke can be released or drawn out from the obstruction as it entered and the vessel can proceed without loss or inconvenience. It will be noticed the strain will always be at an angle de- 55

fined by the relative position of the fluke engaged with the bottom and the upper pivot studs 15-15. Under stress the head 14 can only turn to the angle of the pull, and the tongue 13 in lower end of head 14 geared in the groove 12 between twin tongues in the upper end of auxiliary shank 2 will hold the auxiliary shank captive centrally between controlling shank bars and the shank will perform as one unit. When the anchor is fouled the scope of cable is unchanged and the vessel is moved in the opposite direction thus swinging elements 17 to the dotted line position Fig. 4 and freeing the anchor. It will be further noticed in casting that this anchor will always fall on the bottom in a closed position with both the flukes 7-7 against the shank and when the vessel sets back on the anchor cable, the upper arm 6 will still lie against shank and be non-fouling. The under fin 8 will cause the under arm 6 to open automatically and the under fluke 7 will engage the bottom automatically in the regular manner, while the entire shank continues to remain as one unit. The upper arm 6 will continue to lie against the shank, until the tide changes, when the shank will be drawn to the opposite direction as one unit, and the stock 1 will cause the anchor to turn over on its opposite fin 8 and arm 6 and repeat the above operation. This operation will continue to repeat as long as a fluke is not fouled and the shank will continue to perform as an anchor with the commonly used solid shank.

The stock 1 is provided with a bronze stud in one half, and the other half bored and tapered to receive the other half of said stud, to connect stock in crown and to facilitate detaching stock for stowing when not in use as an anchor. The stock 1 operates to cause one or the other of the arms 6 to take position and its fin 8 will cause one or the other of the flukes to engage the bottom automatically in the regular manner.

The anchor herein described is of simple and cheap construction, and while fulfilling all the requirements of a boat anchor having a one-piece solid shank, has also the capability of being freed from an obstruction on the bottom, thereby reducing the chances of loss to a minimum.

Other features of this anchor are: The entire shank is free from obstructions and is non-fouling; it will haul in hawsepope on vessels out of the way; the upper arms and flukes are non-fouling as they always lie against shank when the lower fluke engages the bottom in the regular manner; and the device is neat in appearance, and inexpensive in the replacement of parts.

Having described my invention, what I claim and desire to secure by Letters Patent is:

1. An anchor comprising a shank made of two parallel parts, a member pivoted to one end of each of said shank parts adapted for connection to an anchor chain, an auxiliary shank having a crown at one end, said auxiliary shank being pivoted adjacent said crown between said shank parts and at the other end of said shank parts from that to which said anchor attachment member is attached, the end of said auxiliary shank opposite said crown being swingable between said shank parts and adapted to cooperate with an end of said member, a pair of arms having flukes thereon independently pivoted to said crown and extending in opposite directions and having fins thereon adjacent said pivots to independently swing said arms whereby said flukes engage the bottom, said fins cooperating with said crown to limit the outwardly pivotal movement of said arms, whereby said anchor functions substantially as and for the purpose set forth.

2. An anchor as set forth in claim 1 wherein a stock is provided for said crown extending on either side of said crown and at right angles to said flukes and auxiliary shank.

GEORGE EDWIN STUBBS.
